J. H. Rosenblatt

ATTORNEY

UNITED STATES PATENT OFFICE.

PAUL E. HELLER, OF NEWARK, NEW JERSEY.

GOLF CLUB.

Application filed March 22, 1927. Serial No. 177,254.

This invention relates to golf club construction and has for its object to produce an improved structure of the type employing a tubular metal or steel shaft and is designed particularly to provide a more durable attachment between the shaft and head portions of the club and wherein there shall be present a desirable resiliency providing an elastic rebound of the head portion from both vertical and torsional or horizontal displacement under impact.

The improved golf club structure of the present invention is of the general type disclosed in my prior patent No. 1,551,563 issued under date of Sept. 1, 1925 wherein a rubber sleeve is interposed between the head member and the lower end portion of the shaft. In addition to providing a desirable resiliency between the head and shaft portions of the club, the rubber sleeve member positioned under compression between the head and shaft has proven to be highly desirable by reason of its high securing value in providing a firm and durable attachment between the parts. The present invention comprises further improved features of construction designed to facilitate the assembling of the structure with resulting economy of manufacture and to possess other features and advantages with reference to firmly securing the parts in position while retaining the desirable resiliency aforesaid.

The described and other advantages of my improved construction will be more readily understood by reference to the accompanying drawing wherein like reference characters are applied to the corresponding parts in the several views.

In the drawings:

Fig. 1 is a view in elevation illustrating a club of the driver or brassie type made in accordance with my invention.

Fig. 2 is a detail view of the lower portion of the club embodying the features of my invention and shown partially in central vertical section.

Fig. 3 is a detail sectional view of the tubular shaft portion prior to expansion of its split end portion.

Fig. 4 is a detail sectional view showing the shaft end expanded into final position by the driving in of the wedge member.

Fig. 5 is a detail sectional view showing a desirable modified construction adapted for incorporating features of the present im-

provements with a wooden shaft type of club.

Fig. 6 is a detail sectional view showing a further modified structure wherein the bore of the head is tapered from both ends.

In the drawings, wherein there is shown a suitable embodiment of the features of my invention, 1 indicates the usual shaft having the handle portion 2 at its upper extremity and having the usual club head 3 mounted upon the reduced lower end portion 4 of the shaft. The head proper is of approved form having the usual upwardly curved neck portion 5 integrally formed therewith and provided with a longitudinal cylindrical bore 6 for the reception of the lower shaft end portion.

The lower end of the shaft, as illustrated, is fitted within the bore and a sleeve of rubber or other suitable resilient material is fitted within the bore throughout the length thereof and interposed between the shaft and the wall of the bore 6 to permit of relative movement and resilient action between the club head and the supporting end of the shaft. The resilient sleeve is shown at 7 and extends from the lower end of the bore upwardly for the full length of the bore and slightly above if desired.

In accordance with my present improvements the steel shaft may be made by first forming a blank of sheet metal as shown in Fig. 5 which progressively diminishes in width toward one end (the end forming the lower portion of the shaft) to a point noted at $\alpha-\alpha$, the remaining or extreme end portion being of uniform width as here shown for a length substantially one half that of the head bore. The end portion of the shaft blank is further provided with the longitudinally extending cut or slit 9 and the shaft is formed by rolling over of the blank and uniting the longitudinal side edges by a suitable welding operation. The resilient member or rubber sleeve may normally be of tubular form and of uniform thickness of its wall and in the assembling of the device it desirably has an adhesive or rubber cement applied to its external surface for firmly securing it to the head portion of the club.

Upon being positioned within the bore of the head, as shown, the shaft formed in the manner described and having its lower portion of the form as shown in Fig. 3, is forced within the rubber sleeve whereby the taper of

the shaft will operate to effect a desirable compression of the upper portion of the rubber sleeve or resilient member. With the parts in final position, a wedge element or 5 tapered plug 10 is forced or driven upwardly into the lower split portion of the shaft end whereby this lower end portion of the shaft is spread or expanded into flared form having its wall in opposite inclination to that 10 of the upper shaft portion as best illustrated in Fig. 4. The insertion of the plug 10 in similar manner effects a compression of the resilient sleeve member with respect to the lower end portion thereof from which it results that the head and shaft are firmly secured against displacement. As will be 15 understood, a suitable cement may likewise be employed between the engaging surfaces of the resilient sleeve and the shaft for obtaining additional security. The tapered plug member 10, as here shown of truncated conical form, may desirably be made of 20 aluminum or of suitable hard wood as preferred.

25 There is thus produced a golf club of improved construction having a resilient sleeve element incorporated therewith so as to provide a desirable resiliency between the head and shaft. The structure accordingly provides for rebound both in the vertical and in the torsional sense so that while possessing the advantages of the steel shaft, a more effective stroke is obtained and which in its action simulates the elastic and yielding effect attained with the better grade of wooden shaft. The improved structural features of 35 the present invention further allow of important production economies in the manufacture of clubs incorporating the desirable features aforesaid and in addition produce 40 an improved club having a particularly effective and durable connection between the head and shaft members.

While I have disclosed an approved embodiment of the features of the present invention, it will be understood that varied modifications may be made without departing from the scope of the invention as defined in the appended claims. As illustrative thereof, I have shown in Fig. 6 a suitable modified structure wherein the bore of the head portion has its wall tapered or inclined inwardly from its upper and lower ends thereby contributing a mechanical bonding effect giving additional holding value by reason of the interlocking relation of the parts.

Having described my invention, I claim:

1. A golf club comprising a shaft and a

head member mounted thereon, said head member being formed with a connecting portion having a bore to receive the shaft end, a rubber sleeve fitted within the bore and interposed between the wall of the bore and the shaft, said shaft being of tubular metal 65 and a tapered wedge forced into the lower end portion of the shaft for expanding the shaft end for securing the parts and to effect compression of the sleeve, substantially as described.

2. A golf club comprising a shaft and a head member mounted thereon, said head member being formed with a connecting portion having a bore to receive the shaft end, a rubber sleeve fitted within the bore and 75 interposed between the wall of the bore and the shaft, said shaft being of tubular metal of progressively decreasing diameter toward its lower end and fitted within the sleeve to compress the latter and a tapered wedge 80 member forced into the lower end portion of the shaft for expanding the shaft end to secure the parts and to effect compression of the sleeve.

3. A golf club comprising a shaft and a head member mounted thereon, said head member being formed with a connecting portion having a bore to receive the shaft end, a resilient sleeve fitted within the bore and interposed between the wall of the bore 90 and the shaft, said shaft being of tubular metal of progressively diminishing diameter toward its lower end and fitted within the sleeve to compress the latter and having its lowermost portion split and a tapered wedge 95 element forced within the lower slit portion of the shaft for expanding the shaft end to secure the parts and to effect compression of the sleeve member.

4. A golf club comprising a shaft and a head member mounted thereon, said head member being formed with a connecting portion having a bore to receive the shaft end, a rubber sleeve fitted within the bore and interposed between the wall of the bore and 105 the shaft, said bore having its wall inclined inwardly from its upper and lower ends to be of reduced diameter at its central portion, said shaft being of tubular metal and a tapered wedge element fitted within 110 the lower end of the shaft for expanding the shaft end portion and to effect compression of the sleeve.

Signed at Newark, in the county of Essex and State of New Jersey this 7th day of December, A. D. 1926.

PAUL E. HELLER.
